UNITED STATES PATENT OFFICE.

JOHN P. WEIS AND ROBERT R. HUGHES, JR., OF NYACK, NEW YORK, ASSIGNEES TO
LUCIUS N. LITTAUER, OF GLOVERSVILLE, NEW YORK.

COMBINED RUFFLING, TRIMMING, AND OVERSTITCH SEWING MECHANISM.

1,111,339.

Specification of Letters Patent. Patented Sept. 22, 1914.

Application filed June 30, 1911. Serial No. 636,185.

To all whom it may concern:

Be it known that we, JOHN P. WEIS and ROBERT R. HUGHES, Jr., citizens of the United States, both residing at Nyack, in the county of Rockland and State of New York, have invented certain new and useful Improvements in Combined Ruffling, Trimming, and Overstitch Sewing Mechanism, of which the following is a specification.

10 This invention relates to improvements in sewing machines, the object of the invention being to provide a sewing machine having combined overstitch, ruffling and trimming mechanisms coöperating in such a manner 15 that the work may be ruffled, the edges trimmed and such trimmed edges overstitched to make a tight and neatly covered seam, so that the work may be completed on one machine, and in which machine also the 20 ruffling mechanism may be thrown into or out of operation as the character of the work requires, thus effecting a large saving and greatly increasing the production, while insuring more uniform work.

25 Heretofore, in the manufacture of under-wear, shirt waists, kimonos and similar garments, it has been the usual practice, where the seams required one portion to be ruffled, another portion to be plain stitched, without 30 any ruffle, and another portion where one ply work is to be ruffled and stitched to another ply of non-ruffled work and the raw edges of such seam covered with an over-stitch, to accomplish this by first ruffling or 35 gathering that portion of the work on a machine prior to its being seamed to the non-ruffled piece of work, so that to complete the seam necessitated three separate operations, first, the ruffling of one piece, then the seaming of the two together, and finally the trimming off of the rough edges, and then over-stitching the seam; whereas, by the present 40 improvement, these three operations are all done at one and the same time, by ruffling 45 one layer of the work as the same is fed to the other layer thereof, trimming the edges of the work prior to the stitching, and then over-stitching the trimmed edges.

A further object of the invention is the 50 provision, in a machine of the character described, of an improved ruffling mechanism which is effective to ruffle the work from the bottom, so that the mechanism is to a certain extent out of the way and the needle is readily accessible for threading and other pur-

poses, while the work can be readily seen and inspected.

In the drawings accompanying and forming part of this specification, Figure 1 is a front elevation illustrating the combined 60 ruffling, trimming and feeding mechanism; Fig. 2 is a left hand end view of Fig. 1; Fig. 3 is a perspective view showing the work produced by the machine partly ruffled, 65 trimmed and overstitched; Fig. 4 is a perspective view of a portion of the presser foot and illustrating the manner in which the toothed wheel engages openings in certain classes of work to facilitate the guiding of the work in a uniform manner; Fig. 5 is a 70 perspective view, partly in section, of details of the mechanism shown in Fig. 1; Fig. 6 is a detail side view, partly in section, of the trimmer mechanism looking toward the left in Fig. 1; Fig. 7 is a detail side view of the 75 ruffling mechanism illustrating more particularly the manner in which the ruffling blade coöperates with the top and bottom stripper members or blades; Fig. 8 is a top 80 plan view of the cloth plate and the means for shifting the top stripper blade to enable the work to be inserted in position; and Fig. 9 is a front view of the mechanism shown in Fig. 8.

Similar characters of reference indicate 85 corresponding parts throughout the figures of the drawings.

In the embodiment shown the bed plate 1 of the sewing machine head has the usual overhanging upright or arm 2 terminating 90 in the gooseneck 3 carrying the usual needle bar 4 and presser bar 5, the former carrying the usual needle 6 and the latter the presser foot 7. Carried by a suitable support or upright 8 is the cloth plate 9 attached thereto 95 in the usual manner. Supported by this upright 8 and the upright 2 is the main driving shaft 10, to which rotary motion is imparted by means of a hand wheel and belt, not shown, and from which the needle bar is 100 caused to reciprocate through some suitable train of mechanism, not shown.

The feed mechanism, which may be of the usual type, and of which therefore a detailed description is unnecessary, comprises in a 105 general way the serrated feed member 11 operating through the usual opening 12 in the throat plate 13 and the work or cloth plate, and coöperates with the presser foot secured to the presser bar in the usual manner. For 110

operating this feed member an adjustable crank disk 14, operated by the main driving shaft, imparts movement to a connecting member 15 pivotally connected to a rocker frame 16 pivotally supported at its lower end on the frame of the machine, the feed member being connected by a bar 17 with the upper end of this rocker frame 16. The usual feed lift eccentric, not shown, gives the 10 rise and fall movement to the feed bar and feed member through the connection indicated by 18, shown in dotted lines in Fig. 2. The presser foot 7 may be secured in any desired manner and is turned up at an angle at 15 its front end, see Figs. 2 and 7, as at 19, and in the present instance is provided with a slot 20 in which is mounted for rotary movement a toothed wheel 21. This slot in the foot is made wider than the width of the 20 wheel and thus enables said wheel to be adjusted laterally by means of a guiding fork 22 secured to the upturned portion of the presser foot. The presser foot is also provided with an extension 24 at the side thereof, see Fig. 4, which is in position to reach 25 around the trimmer knife hereinafter described and thus forms a means for holding that portion of the work to be trimmed down so that it will not get over the top of the 30 knife and thus prevents such trimmed portion from again getting into the path of the knife or needle.

This improved ruffling mechanism comprises in a general way a pair of stripper members or blades and a ruffler having a movement therebetween, whereby the work is ruffled from the underside or bottom thereof, together with means for operating the ruffler, and which ruffling mechanism is provided with means for throwing it into and out of action, whereby parts of the work may be plain stitched while other parts thereof may be ruffed, and also with means for adjusting the ruffler blade whereby a 45 greater or less ruffle may be obtained, and also with means whereby one, as the upper, stripper plate or blade may be shifted to facilitate the insertion of the work, and which several means may be operated by 50 the operator without requiring the use of the hands, which thus may be left free to manipulate the work. The ruffling mechanism is located below the upturned portion of the presser foot and in position to properly feed the work under the straight or flat portion of the presser foot, and comprises a top or upper stripper plate or blade 30 and a lower or bottom stripper plate or blade 60, and a ruffler or ruffling 55 member 70. The upper or top stripper plate or blade 30 is adjustably secured in a slot 31 of a suitable holder 32 by means of a washer and nut 33, which holder is secured to an overhanging bracket 34. 60 This bracket extends back and terminates

in a plate or enlargement 36 adjustably secured to the cloth plate 9 by means of screws 35.

As in certain classes of work it is desirable to shift or raise the stripper plate or blade so as to leave sufficient space between it and the ruffling blade to permit the bottom ply of work to be readily inserted and to also facilitate the insertion of the upper ply of work, thereby to permit the even starting of both plies of work, the stripper blade holder is secured to a rock shaft 37 supported by suitable bearings 38 on the bracket 34, and this shaft is provided with a forked crank arm 39, coöperating with which is a pin 39' carried by a crank arm 40 secured to a rock shaft 41 supported in a suitable bearing 42 carried by the bracket 34. This shaft 41 is provided with a collar 44 secured to the presser foot 45, which extends downwardly and is provided with a coupling 46 connecting the same with a rod 47 carrying a spring 48 so located that it returns the rod to its normal or lifted position. 50 To the lower end of this rod is connected a chain 49, usually connected to a treadle, not shown, usually located on the floor, or to a knee shift, whereby it may be readily operated by the foot or knee of the operator. This rod and chain mechanism is connected to the presser foot in the usual manner for lifting the presser foot so as to permit both hands of the operator to remain free to manipulate the work. As 100 the presser foot is usually raised to permit the insertion or removal of the work, it will be apparent that the operation of this mechanism through the means just described will also simultaneously lift the top 105 stripper blade. A coiled spring 50 encircles the shaft 37 and coöperates with a collar 51 and the left hand bearing 38, thereby to normally keep the top stripper blade in contact with the bottom stripper blade. 110 An adjustable work guide 52, see Fig. 5, is adjustably attached to the cloth plate to project into position below the upper stripper blade and in such position that it will facilitate the guiding of the lower ply of 115 work to be ruffled. The bottom stripper plate or blade 60 is secured at 61 to a bracket 62 and coöperates with the upper or top stripper blade 30 in such a manner as to receive the ruffle from the ruffling 120 plate and clamp it while the ruffling plate or blade is withdrawn therefrom, thus insuring a positive ruffle at each movement or reciprocation of the ruffling blade and overcoming any tendency on the part of 125 the operator to straighten out the ruffle after it has once been formed.

The ruffling blade 70 is of spring or resilient formation, as are also the upper and lower stripper blades, and is adjustably se- 130

cured to a flattened off portion 71 of the ruffling blade holder 72. This ruffling blade 70 is formed to extend up through an opening in the throat plate with its 5 toothed end 73 in position between the upper and lower stripper blades, and this ruffling blade 70 is also provided with a curled lip 74 coöperating with the bottom of the throat plate in such a manner as 10 to limit the upward movement of the blade through the throat plate. The ruffling blade holder 72 is cylindrical in form for the reception of a shoulder screw 75, and around this holder a coiled spring 76 is 15 located, one end of the spring resting underneath a portion of the ruffling blade holder, as at 77, while the other end of the spring is clamped by the screw 75. This affords a means of regulating the tension of this 20 spring on the ruffling blade and its holder and causes the curled lip 74 to engage the bottom of the throat plate.

The ruffling blade holder 72 is secured to a curved segment or arm 86, which is pivotally secured by a shoulder screw 83 to a bracket 84 attached to the base plate of the machine, as at 85. This bracket is provided with a socket in which is secured a post 87 carrying two adjustable stops 88 and 89 for 30 the purpose of limiting the movement of the block and connection about to be described.

Pivotally secured to the feed dog connecting member 15 is a connecting member or rod 90, by means of which connection this 35 rod 90 has movement imparted thereto from the adjustable crank 14. This movement is the same in extent as the movement of the feed mechanism, and this connecting member 90 has attached thereto a segmental slide 40 block 91 by means of a shoulder screw 92, which slide block moves freely on the curved segment or arm 86, movement thereof being limited by the stops 88 and 89 secured to the post 87 hereinbefore described. By 45 means of these adjustable stops 88 and 89 the movement of the block along the segmental arm is limited, so that two predetermined adjustments may be obtained, that is to say, if the lower stop is adjusted as 50 low as possible on its post and the other as high as possible the block may be caused to slide to the top of the curved segment or to the bottom thereof and is locked in either position by the set screw 93, shown in dotted 55 lines in Fig. 2. This curved segment is graduated, as at 94, so that by adjusting the block to the desired position the amount of ruffle desired may be obtained, it being apparent of course that the movement of the 60 crank disk 14 imparts reciprocatory movement through the curved segment to the ruffling blade to ruffle the lower ply of material, as shown in Fig. 3, under the upper 65 ply of material, in other words, to ruffle the work from the bottom thereof. In practice

the thumb screw 93 may be omitted or left unfastened, so that the segmental block 91 may be shifted without the necessity of using the hands for this purpose. To accomplish this, the block 91 has pivotally secured thereto, see Fig. 9, a connecting rod 95, the lower end of which extends downward below the work table and is pivotally secured to a rocking lever 96 pivotally secured to a bracket supported at the underside of the table. The 70 opposite end of this lever has pivotally connected thereto a rod 97 extending upward through the table and is provided at its upper end with a pad or rest 98 in position to be operated by the arm or wrist of the 80 operator, and is conveniently located so that while both hands of the operator are engaged in guiding the work this rest or pad may be depressed by the arm of the operator and so operate it to shift the slide block 91 85 along the curved segment to the positions determined by the stops carried by the post.

Attached to the connecting members 15 and 90 is a pair of links 100, 101, connected at their lower ends by a helical spring 102, 90 and this normally causes the segmental slide block to move to the lowest position on the curved segment determined by the lowest stop, so that it will be observed that after pressure is removed from the rest shown in 95 Fig. 9 the lever mechanism and the slide block will be caused to descend to its lowest position on the curved segment.

When the segmental block 91 is moved downward it increases the throw of the 100 ruffling blade and hence increases the amount of ruffle, and by shifting this block upward the amount of ruffle is decreased or entirely prevented, so that the two plies of work may be stitched by the usual stitches without any ruffling of one of them; so that when the operator, through the mechanism hereinbefore described, shifts the block downward on the graduated arm the amount of ruffle will be increased according to the distance that the block is shifted downward. When the segmental block 91 is at the 105 extreme upper end of the graduated arm the ruffling mechanism is out of operation so far as any ruffling action thereof is concerned.

The bottom stripper blade acts resiliently 110 simply to strip the ruffle from the ruffling blade; in other words, it prevents the ruffle from pulling back or straightening out, it being forced down by the ruffling blade when the same is shifted forward to ruffle the goods. The ruffling blade engages the goods to be ruffled and forces it between the stripper blades, the lower stripper blade being so 115 adjusted that the ruffer blade in its movement toward the needle projects slightly over this stripper blade to deposit the ruffle upon it and underneath the upper stripper blade 120 hereinbefore referred to.

The toothed wheel of the presser foot is useful to assist in guiding lace insertions, etc., the teeth of the wheel engaging the open work of the insertion to facilitate the guiding of the work and maintaining a uniform distance from the open spaces of the work to the line of stitch.

In practice the upper layer or ply of work that is to be stitched passes over the upper 10 stripper blade in the manner shown in Fig. 7, it running in straight, without turning, so that the edge lies flat. The stripper blade 30 is adjustable toward and from the needle in the slot of the holder which carries it, and 15 the holder also has a swinging adjustment relatively to the overhanging bracket 34, so that the stripper blade may be adjusted into any desired position. The under layer or 20 ply which is to be ruffled is fed between this stripper blade and the ruffler, being suitably guided by the guide hereinbefore described and in the manner shown in Fig. 7, whereupon the ruffler ruffles the under layer of goods. As the work is ruffled the edge 25 comes jagged or irregular, and by providing the trimming mechanism hereinafter described this edge, together with an irregular edge of the upper layer, is trimmed off smooth and is then fed by the feed dog to 30 the stitching mechanism, where the edges are stitched by the overlock stitching mechanism in the manner hereinafter described. The adjustable guide 52 regulates the amount to be trimmed off of the piece that is being 35 ruffed and can be so adjusted that the margin to be trimmed off will be the exact amount required, whether it be one-eighth or one-quarter of an inch.

From the foregoing it will be observed 40 that in the present improvement, by the proper manipulation of the ruffler through the means provided for that purpose, part of the work can be stitched plain while another part can be ruffed the required 45 amount, some part of which for instance to a greater extent than another part thereof; or, if preferred, the same amount of ruffle may be obtained at all times by setting the 50 stops 88 and 89 on the upright post, or by tightening up the thumb screw 93 hereinbefore referred to.

By having the links 100 and 101 projecting downward the spring 102 connected thereto normally holds the segmental block 55 on the graduated segment in its lowest position. If, however, these links 100 and 101 were reversed and projected upward the result would be that the sliding block on the graduated segment would be held in its uppermost position, so that no ruffling whatever would occur, provided of course the stops on the upright post were adjusted in their proper positions to permit this.

The trimming mechanism does not require 60 a detailed description herein.

Secured to the main driving shaft 10 is the trimmer driving eccentric 105, which imparts movement to an eccentric strap 106 having a tubular stem 107 in which a spring 108, see Fig. 6, is located and engages a piston 109 connected to the trimmer lever 110 at 111. A latch lever 112 is also secured at 111 and co-operates with a stud 113 carried by a collar 114, which is adjustably secured to the tubular stem 107. By manipulating 15 this latch to cause the same to engage the stud or pin 113 the piston is rigidly connected with the tubular stem 107, so that movement will be imparted by the rotary 20 driving shaft to the trimmer lever and its 25 knife, and by disconnecting these parts, together with the catches hereinafter referred to, the trimmer may be removed from the machine.

The trimmer or knife lever 110 is supported by a short shaft 116 carried by bearings 117 of a trimmer supporting frame 118, said lever having a hub 119 through which the shaft passes. One arm of this lever 110 carries the knife 120 secured to it at 121. A metal guard 122 is also attached to this arm of the lever along its entire length by solder or any other suitable means, and this arm acts as a diverter to divert the trimmings away to one side where they will drop to 95 the side of the machine owing to the fact that this arm is constantly vibrating while the trimmings are dropped thereon. The vibrating knife 120 co-operates with a stationary blade 123 clamped to the trimmer 100 supporting frame by a lever 124, which is secured to an extending portion of the trimmer frame, as at 125. This lever extends out beyond the front of the trimmer frame to form a handle which may be manipulated 105 to unclamp the stationary knife when it is desired to remove the same. The trimmer supporting frame 118 is provided with a pair of pins 126, one at each side thereof, with which co-operate clamps or catches 127 carried by a trimmer supporting bracket 128, which is adjustably secured to the base plate of the machine, and these catches rigidly hold the trimmer frame in position on the trimmer bracket, and by disconnecting 110 these latches and the latch lever 112 the trimmer frame and its parts may be removed from the machine. Secured to the bracket 128, see Fig. 1, is an adjustable gage 129, it being secured thereto by means 115 of a screw 130. This gage is provided with vertical extensions 131 between which the trimmer supporting frame rests. The trimmer supporting bracket being wider than the trimmer supporting frame enables the 120 latter to be adjusted laterally by loosening the screw 130 and adjusting the gage 129. When once adjusted the trimming mechanism may always be replaced so that its 125 position relative to the line of stitches will be 130

the same. The trimmer blade cuts a shearing cut, and by disconnecting the latch lever 112 the vibrating blade is thrown out of action, so that if the work should require a little mending or other attention this can be readily done. After the work is ruffled and trimmed it is fed to the stitching mechanism, which in the present instance comprises an overseam stitching mechanism, a detailed description of which, however, is deemed unnecessary herein.

Secured to the driving shaft is an eccentric strap 140, which imparts motion to a connection indicated by 141. Operating in the top of this connection 141 is a ball stud 142 having an end thereof clamped to the crank 143 by means of a screw 144. This crank is secured to a shaft 145 carried by a bracket 146, shown in section in Fig. 5, and by this means the carrier 147 is caused to operate in the manner hereinafter described. In another bearing 148 of the bracket 146 is located a shaft 149 carrying a link 150 pivotally connected to the carrier 147. This carrier 147 is provided at its upper end with a socket 151 in which is secured a loop spreader 152, see Fig. 5.

Secured to the driving shaft 10 is a bevel gear 155, see Fig. 2, in mesh with a suitably supported similar bevel gear 156, which last gear is connected by a link 157, see Fig. 1, with a looper carrier 158 pivotally supported at its lower end by a shaft 159 mounted in a bracket 160, and in which bracket this shaft is free for movement. The upper end of this carrier is provided with a looper 161, and by the mechanism just described reciprocatory motion is imparted to the looper, and with which looper the needle hereinbefore referred to cooperates. The looper carries a thread that is passed thereby through the needle loop carried by the needle, at which time the spreader 152, which also carries a thread, is in such position as to enter the looper loop and rise up over the edge of the work and present a loop of its thread to the needle, thus producing a three-thread lock overseam.

We claim as our invention:

1. In a sewing machine, the combination of stitching mechanism, feeding mechanism for feeding the work to and past the stitching mechanism and comprising a feed dog and means for operating the same, ruffling mechanism independent of and located in advance of the feeding mechanism and including a ruffling blade and a swinging arm connected thereto located at the feeding end of the machine, means connecting said swinging arm with the feeding mechanism, means effective to adjust the parts of the ruffling mechanism thereby to vary the amount of ruffle or to render the ruffling mechanism ineffective to ruffle, trimming

mechanism, stitching mechanism, and means for operating the several mechanisms simultaneously.

2. In a sewing machine having a throat plate, the combination of a ruffler comprising a blade supported below the plane of said plate and projecting upwardly above said plate and downwardly toward the same and in position to operate at the underside of the work, and means for actuating said blade.

3. In a sewing machine having a throat plate, the combination of ruffling mechanism comprising a stripper blade located to work above said plate and a ruffler supported below the plane of said plate and projecting thereabove and downwardly toward said plate for ruffling on the underside of the work, and means for operating said ruffler.

4. In a sewing machine having a throat plate, the combination of ruffling mechanism comprising a stripper blade located to work above said plate, a ruffler supported below the plane of said plate and projecting thereabove and downwardly toward said plate for ruffling on the underside of the work and a stripper blade located below the plane of said plate for coöperating with the ruffler at the underside of the work, and means for operating said ruffler.

5. In a sewing machine having a throat plate, the combination of ruffling mechanism comprising a stripper blade located above said plate and a ruffler supported below the plane of said plate and projecting thereabove for ruffling on the underside of the work, means for operating said ruffler, means for limiting the movement of said ruffler, a stripper blade located below the plane of the throat plate, and means for raising the first stripper blade without affecting the position of the ruffler.

6. In a sewing machine having a throat plate, the combination of ruffling mechanism comprising a stripper blade located above said plate and a ruffler supported below the plane of said plate and projecting thereabove for ruffling on the underside of the work, means for operating said ruffler, means for limiting the movement of said ruffler, and a stripper blade supported below the plane of said throat plate and coöperating with the ruffler blade and said first stripper blade.

7. In a sewing machine having a throat plate, the combination of a ruffler blade supported below the plane of said plate and projecting above the same and comprising a resilient member bent to project upwardly through the throat plate and then downwardly toward the same.

8. In a sewing machine having a throat plate, the combination of a presser foot having an upturned end, ruffling mechanism

- comprising a stripper blade supported above the plane of said plate and projecting below the upturned end of the presser foot, a ruffler blade supported below the plane of said 5 throat plate for reciprocatory movement, means for reciprocating it, and a stripper blade supported below the plane of the throat plate and operating at the underside of the ruffler blade.
10. In a sewing machine having a throat plate, the combination of a ruffler blade supported below the plane of said plate and projecting above the same and comprising a resilient member, means for varying the 15 movement of said ruffler blade, a stripper blade located above the plane of said throat plate and also comprising a resilient member, and a stripper blade supported below the plane of said throat plate and also comprising 20 a resilient member.
10. In a sewing machine having a cloth plate provided with a throat plate, the combination of ruffling mechanism comprising a stripper blade over which one layer of material is fed, a ruffler blade supported below the plane of the throat plate and between which and said stripper blade another layer of material is fed and a stripper blade supported to work below said ruffler blade, and 25 means for reciprocating the ruffler blade, said ruffler blade and last stripper blade projecting above the throat plate.
11. In a sewing machine having a cloth plate provided with a throat plate, the combination of ruffling mechanism comprising a stripper blade over which one layer of material is fed, a ruffler blade between which and said stripper blade another layer of material is fed and a stripper blade supported 30 below said ruffler blade, means for reciprocating the ruffler blade, said ruffler blade and last stripper blade supported below the plane of but projecting above the throat plate, and means for varying the reciprocatory 35 movements of said ruffler blade or throwing it into an ineffective position to ruffle.
12. In a sewing machine having a cloth plate provided with a throat plate, the combination of ruffling mechanism comprising a stripper blade over which one layer of material is fed, a ruffler blade between which and said stripper blade another layer of material is fed and a stripper blade supported 40 below said ruffler blade, means for reciprocating the ruffler blade, said ruffler blade and last stripper blade supported below the plane of but projecting above the throat plate, means for varying the reciprocatory 45 movements of said ruffler blade or throwing it into an ineffective position to ruffle.
13. In a sewing machine having a cloth plate provided with a throat plate, the com- 50
- bination of ruffling mechanism comprising a stripper blade over which one layer of material is fed, a ruffler blade between which and said stripper blade another layer of material is fed and a stripper blade supported 55 below said ruffler blade, means for reciprocating the ruffler blade, said ruffler blade and last stripper blade supported below the plane of but projecting above the throat plate, means for varying the reciprocatory 60 movement of said ruffler blade or throwing it into an ineffective position to ruffle, and means for shifting the upper stripper blade thereby to facilitate the feeding of the work.
13. In a sewing machine having a cloth plate provided with a throat plate, the com- 65
- bination of ruffling mechanism comprising a stripper blade over which one layer of material is fed, a ruffler blade between which and said stripper blade another layer of material is fed and a stripper blade supported 70 below said ruffler blade, and means for reciprocating the ruffler blade, said ruffler blade and last stripper blade projecting above the throat plate and said ruffler blade having a part thereof in engagement with the underside of the throat plate thereby to limit the upward movement of said blade. 75
14. In a sewing machine, the combination of stitching mechanism and ruffling mechanism, the latter comprising a reciprocating ruffling blade located in position to work on the underside of the work and a pair of stripper blades one supported to work above and the other to work below the ruffler blade, means for reciprocating the ruffler blade and comprising a sector and a member movable thereon, stops for limiting the reciprocating movement of said ruffler blade, and means for varying the reciprocatory movement of the blade and throwing it into an ineffective 80 position to ruffle. 85
15. In a sewing machine, the combination of stitching mechanism and ruffling mechanism, the latter comprising a reciprocatory ruffling blade located in position to work on the underside of the work and a pair of stripper blades one supported above and the other below the ruffler blade, means for reciprocating the ruffler blade and comprising a sector and a member movable thereon, stops for limiting the reciprocating movement of said ruffler blade, and means for varying the reciprocatory movement of the blade and throwing it into an ineffective 90 position to ruffle. 95
16. In a sewing machine, the combination of stitching mechanism and ruffling mechanism, the latter comprising a reciprocatory ruffling blade located in position to work on the underside of the work and a pair of stripper blades one supported above and the other below the ruffler blade, means for reciprocating the ruffler blade and comprising a sector and a member movable thereon, stops for limiting the reciprocating movement of said ruffler blade, means for varying the reciprocatory movement of the blade and throwing it into an ineffective position to ruffle and comprising means shiftable by the operator while permitting the hands of the operator 100 to be free to manipulate the work. 105
17. In a sewing machine, the combination of stitching mechanism and ruffling mechanism, the latter comprising a reciprocatory ruffler blade located in position to work on the underside of the work and a pair of stripper blades one supported above and the other below the ruffler blade, means for reciprocating the ruffler blade and comprising a sector and a member movable thereon, stops for limiting the reciprocating movement of said ruffler blade, means for varying the reciprocatory movement of the blade and throwing it into an ineffective position to ruffle, and an adjustable work guide located below the upper stripper blade for guiding one layer of work between said blade and the ruffler blade. 110 115 120 125
17. In a sewing machine, the combination of stitching mechanism and ruffling mechanism, the latter comprising a reciprocatory ruffler blade located in position to work on the underside of the work and a pair of stripper blades one supported above and the other below the ruffler blade, means for reciprocating the ruffler blade and comprising a sector and a member movable thereon, stops for limiting the reciprocating movement of said ruffler blade, means for varying the reciprocatory movement of the blade and throwing it into an ineffective position to ruffle, and an adjustable work guide located below the upper stripper blade for guiding one layer of work between said blade and the ruffler blade. 130

stripper blades one supported above and the other below the ruffler blade, means for reciprocating the ruffler blade and comprising a sector and a member movable thereon, 5 stops for limiting the reciprocating movement of said ruffler blade, means for varying the reciprocatory movement of the blade and throwing it into an ineffective position to ruffle, and feeding mechanism including a presser foot having an upturned forward end below which said ruffler blade and stripper blades are located.

18. In a sewing machine having a throat plate, the combination of stitching mechanism and ruffling mechanism, the latter comprising a reciprocatory ruffler blade supported below the plane of said throat plate to work on the underside of the work and a pair of stripper blades one supported to 15 work above and the other to work below the ruffler blade, means for reciprocating the ruffler blade and comprising a sector and a member movable thereon, stops for limiting the reciprocating movement of said ruffler blade, means for varying the reciprocatory 20 movement of the blade and throwing it into an ineffective position to ruffle, and feeding mechanism including a presser foot having an upturned forward end below which said ruffler blade and stripper blades are located.

19. In a sewing machine having a throat plate, the combination of ruffling mechanism comprising a stripper blade over which one 25 layer of material is fed, a ruffler blade effective to ruffle on the underside of the work and between which and said stripper blade another layer of material is fed and another stripper blade supported to work at the underside of the material, and means for reciprocating the ruffler blade.

20. In a sewing machine having a throat plate, the combination of ruffling mechanism comprising a stripper blade over which one 30 layer of material is fed, a ruffler blade supported below the plane of said throat plate and projecting above the same and between which and said stripper blade another layer of material is fed, means for reciprocating the ruffler blade, and another stripper blade 35 also supported below the plane of said throat plate.

21. In a sewing machine, the combination of a ruffling blade, a swinging segmentally shaped arm connected thereto, a block sliding on said arm, means connected with said block for swinging the arm, a plurality of 40 stops in position and adjustable to limit the movement of said block at various points throughout the length of said arm, and means for supporting said stops independently of said arm.

22. In a sewing machine, the combination of a pair of stripper blades, a ruffling blade supported to work therebetween, a swinging 45 segmentally shaped arm connected to

said ruffling blade, a block sliding thereon, means connected with said block for swinging the arm, a plurality of stops in position and adjustable to limit the movement of said block at various points throughout the 50 length of said arm, and means for supporting said stops independently of said arm.

23. In a sewing machine, the combination of a pair of stripper blades, a ruffling blade supported to work therebetween at the underside of the work, a swinging segmentally shaped arm connected to said ruffling blade, a block sliding thereon, means connected with said block for swinging the arm, and a plurality of stops in position and adjustable 55 to limit the movement of said block at various points throughout the length of said arm.

24. In a sewing machine, the combination of a ruffler blade, a swinging arm for supporting said ruffler blade, means connected with said arm for swinging it and adjustable thereon for varying the movement of said blade, and spring controlled means for holding said blade in one or the other of its 60 extreme adjusted positions.

25. In a sewing machine, the combination of a ruffler blade, a swinging arm for supporting said ruffler blade, means connected with said arm for swinging it and adjustable 65 thereon for varying the movement of said blade, spring controlled means for holding said blade in one or the other of its extreme adjusted positions, means for shifting it from such position to or toward its other position, and means for limiting the movement thereof.

26. In a sewing machine having a throat plate, the combination of a ruffler blade supported below the plane of and projecting 70 above said throat plate, a swinging arm supporting said blade, means connected thereto for swinging said arm and adjustable thereon for varying the movement of said blade, a stripper member located above the plane 75 of said throat plate, means for raising and lowering said stripper member, and a stripper blade supported below the plane of said throat plate and coacting with the ruffler blade.

27. In a sewing machine having a throat plate, the combination of a ruffler blade supported below the plane of said throat plate and projecting above the same, a stripper blade supported above the plane of the 80 throat plate, a stripper blade supported below the plane of the throat plate, and means for operating said ruffler blade.

28. In a sewing machine having a throat plate, the combination of a ruffler blade supported below the plane of said throat plate and projecting above the same, a stripper blade supported above the plane of the 85 throat plate, a stripper blade supported below the plane of the throat plate, means for 90

operating said ruffler blade, and means for raising and lowering the upper stripper blade.

29. In a sewing machine having a throat plate, the combination of a ruffler blade supported below the plane of said throat plate and projecting above the same, said ruffler blade having means for limiting the position of the blade relatively to the throat plate, a stripper blade supported above the plane of the throat plate, a stripper blade supported below the plane of the throat plate, means for operating said ruffler blade, and means for raising and lowering the upper stripper blade.

30. In a sewing machine having a throat plate, the combination of a ruffler blade supported below the plane of said plate and having a part thereof projecting above said plate, a swinging segmentally shaped arm supporting said ruffler blade, means connected with said arm for swinging it and adjustable thereon for varying the movement of said ruffler blade, a stripper blade located above the plane of the throat plate, means for raising and lowering it independently of the ruffler blade, and a stripper blade supported below the plane of said throat plate and coöperating with the ruffler blade and the shiftable stripper blade.

31. In a sewing machine, the combination of a ruffler, a swinging arm for supporting said ruffler, means connected with said arm for swinging it and adjustable relatively to said arm for varying the movement of said ruffler, stops for limiting the adjustable movement of said means at any desired point on the swinging arm, and spring controlled means for holding the means connected with the arm against one or the other of said stops.

32. In a sewing machine, the combination of a ruffler blade, a swinging segmentally shaped arm for supporting said ruffler blade, means connected with said arm for swinging it and adjustable thereon for varying the movement of said ruffler blade, stops for limiting the adjustable movement of said means at any desired point on the swinging arm, and spring controlled means for holding the means connected with the arm against one or the other of said stops.

33. In a sewing machine, the combination of a ruffler blade, a swinging arm for supporting said ruffler blade, means connected with said arm for swinging it and adjustable thereon for varying the movement of said ruffler blade, spring controlled means for holding said means in one or the other of its extreme adjusted positions, and means for shifting it from such position to or toward its other position.

34. In a sewing machine, the combination

of a ruffler blade, a swinging segmentally shaped arm for supporting said ruffler blade, means connected with said arm for swinging it and adjustable thereon for varying the movement of said ruffler blade, means for holding said means in one or the other of its extreme adjusted positions, means for shifting it from such position to or toward its other position and comprising arm operated means.

35. In a sewing machine, the combination of a ruffler blade, a swinging arm for supporting said ruffler blade, means connected with said arm for swinging it and adjustable thereon for varying the movement of said ruffler blade, a spring controlled means for holding said means in one or the other of its extreme adjusted positions, means for shifting it from such position to or toward its other position, and means for regulating the tension of the ruffler blade.

36. In a sewing machine, the combination of a ruffler blade, a swinging segmentally shaped arm for supporting said ruffler blade, means connected with said arm for swinging it and adjustable thereon for varying the movement of said ruffler blade, means for normally holding said means at one extreme position on said arm, means for shifting said means to or toward the other extreme position on said arm, and adjustable stops supported in juxtaposition to said arm for limiting the adjustable movement of said means.

37. In a sewing machine, the combination of a ruffler blade, a swinging arm for supporting said ruffler blade, means connected with said arm for swinging it and adjustable thereon for varying the movement of said blade, and reversible spring controlled means for holding said blade in one or the other of its extreme adjusted positions.

38. In a sewing machine, the combination of a ruffler blade, a swinging arm for supporting said ruffler blade, means connected with said arm for swinging it and adjustable thereon for varying the movement of said ruffler blade, reversible spring controlled means for holding said means in one or the other of its extreme adjusted positions, and means for shifting it to or toward its other adjusted position.
